VALVE MECHANISM.

1,120,010.

Specification of Letters Patent.

Patented Dec. 8, 1914.

Application filed September 7, 1912. Serial No. 719,228.

To all whom it may concern:

Be it known that we, HARRY R. ATWATER and EDWIN S. CARMAN, citizens of the United States, and residents of Cleveland, 5 county of Cuyahoga, State of Ohio, have jointly invented a new and useful Improvement in Valve Mechanism, of which the following is a specification, the principle of the invention being herein explained and 10 the best mode in which we have contemplated applying that principle, so as to distinguish it from other inventions.

The present invention relates in general to valve mechanism, and particularly to an 15 automatically acting valve adapted to be used with a jarring molding machine, such as is shown in the Patent No. 1,008,299, issued November 14, 1911, to Harry R. Atwater. The present valve is intended to 20 supplant the valve mechanism which is there shown for controlling the supply and exhaust of air to and from the tubular support.

The present invention may, however, be 25 applied to various other uses wherever an automatically acting plunger valve is desired, since it will be seen that our invention may be adapted with but little change to numerous other constructions.

30 To the accomplishment of the foregoing and related ends, said invention, then, consists of the means hereinafter fully described and particularly pointed out in the claims.

35 The annexed drawings and the following description set forth in detail certain mechanism embodying the invention, such disclosed means constituting, however, but one of the various mechanical forms in which 40 the principle of the invention may be used.

In said annexed drawings:—Figure 1 is 45 a central vertical section through the tubular support of the molding machine and through the valve casing, showing the plunger valve in side elevation; Fig. 2 is a similar view of the valve casing and valve, but showing the latter in a different position; Figs. 3 and 4 are views similar to Figs. 1 and 2, showing the valve plunger 50 in different operative positions, and Figs. 5, 6, 7, 8 and 9 are sections at different points through the valve casing and plunger illustrating details of construction such sections being taken on the lines 5—5, 6—6, 55 7—7, 8—8 and 9—9, respectively; and Figs.

10 and 11 are details of construction, showing the upper end of the stem attached to the valve plunger together with one of the adjusting nuts for the same.

In Fig. 1 there is shown a tubular support 1 in which there is disposed a reciprocable piston member 2 upon the top of which will be carried a suitable pattern plate holder (not shown). The piston member is provided with a laterally projecting shoulder 3 which is adapted to contact and strike against the top of the tubular support. The piston part of the member 2 will be slightly less in length than the depth of the tubular support, thus providing at all times a space between the bottom of the piston and the bottom of the support. Connecting with this space, is a passage 4 leading to the exterior of the support. Attached at the side of the support 5 is a valve casing 5 having an inlet port 6 connected with the pipes 7 leading to a suitable source of fluid pressure supply, and an exhaust passage 8 which may be connected to the pipe 9 leading either to the 10 atmosphere or to a suitable exhaust reservoir, such as a drain. Two openings 10 and 11 connect the interior of the casing with the passage 4 extending through the support, and these two openings will be controlled by the plunger 12 which is reciprocably mounted in the casing. Each of these openings 101 will extend in grooves 13 around the interior of the casing, thus balancing the pressure on all sides of the 15 plunger, and allowing the same to move freely up and down in the casing. In one side of the casing there is disposed a bypass 14 extending slightly below the inlet passage 6 to a point in the upper part of the casing. Such bypass is also extended at the upper end around the interior of the casing in a groove in order to completely equalize and balance any pressure existing against the plunger. Slightly above the 20 upper end of this bypass is an exhaust passage 16 opening into the atmosphere and controlled by the plunger.

It will be noticed that the interior of the casing is formed with various sized chambers, and the plunger is provided with an enlarged portion 17 adapted to reciprocate and to be received only in the upper and larger chamber. From the bottom of this upper chamber a bypass 18 extends to near 25

the top of the same, such by-pass opening into the chamber formed by a cap 19 attached to a valve stem 20, and the top of the casing. This cap 19 is loosely fitted 5 onto the casing, thus permitting the passage of air beneath it and the casing. The upper part of the valve stem is threaded and is adjustably engaged by two nuts 21 and 22. The piston member is formed with 10 a projection 25 which is apertured to receive the valve stem.

The operation of the valve is controlled, to some extent, by the reciprocation of the piston member and by means of the extension 15 and the two nuts 21 and 22. In Fig. 1 the valve is shown in its lowest position completely closing the exhaust passage from the support to the atmosphere or reservoir, and permitting the air to enter beneath the 20 piston through the tube 7 and the passages 6 and 10 around the shaft 26 connecting the two larger portions of the plunger. In such a position the upper nut 21 is resting on the extension 25. When air is admitted 25 beneath the piston, the piston is raised and the plunger is simultaneously raised into an upper position until the exhaust port is within a short distance of opening, as shown in Fig. 4. At this point in the plunger's 30 movement the exhaust port around the support is not open. The portion of the valve normally adjacent to the inlet ports is much smaller in diameter than the rest of the plunger, the two port-controlling portions 35 being connected by a small wrist or shaft 26. The enlarged portion 17 of the plunger has by this movement uncovered the upper end of the by-pass 14 and air is therefore admitted beneath the shoulder on such enlarged portion, thus shooting the plunger 40 upward and opening the exhaust port 11 and closing the inlet port 10 simultaneously. At the time the exhaust port 11 is wide open and the inlet port entirely closed, 45 the enlarged portion of the plunger uncovers the port 16 allowing the air under the shoulder to escape, the valve at this position closing port 14. The weight of the plunger will cause it to drop as soon as the 50 air under the shoulder is exhausted. This downward movement will close the exhaust port 16 and will reopen the by-pass 14, admitting air under the shoulder and shooting the plunger upward, again opening the 55 exhaust port 16, allowing the air to escape and permitting the plunger to again drop. This action is theoretical rather than actual, for the opening of the exhaust port 11 allows the piston member to fall and contact of the extension 25 upon the lower nut 60 22 will force the plunger down. This will be done so rapidly that the fore-going reciprocating action of the plunger will be prevented. The plunger will, of course, be held in such balanced position until the 65

tension 25 has slid along the valve stem 20 into contact with the nut 22, but for all practical purposes this action will be instantaneous. At this point the by-pass port 14 is uncovered again admitting the air 70 under the shoulder of plunger 20, holding nut 22 in contact with lug 25 while the piston 2 is descending, thereby doing away with the necessity of springs, catches, etc. The plunger will now be forced across the 75 inlet and exhaust ports, the opening and closing being simultaneous on account of the lower portion of the plunger being equal in length to the distance between the upper edge of the inlet port and the lower 80 edge of the exhaust port. The position of the adjustable nut 22 on the valve stem will determine to what extent, if at all, the fall of the piston member will be cushioned by compressed air beneath the 85 piston in the support. By moving the nut 22, a considerable cushioning effect may be secured or the piston member may be allowed to strike with its full weight, although in such a machine a slight cushioning will be desirable. The continued 90 downward movement of the plunger will uncover the second by-pass 18, thus allowing the air beneath the shoulder to escape into the chamber between the cap 19 and the top of the valve casing. From here the air is allowed to discharge by reason of the loose fit between the cap and the casing.

Lubrication of the plunger is secured by three oil grooves 30, 31 and 32 (see Fig. 9) 100 connected by a passage 33 with an opening 34 to which may be attached an oil reservoir. Each bearing surface of the plunger is lubricated by one of these grooves which extend completely around the casing and are so disposed relatively to the movement of the plunger, that the grooves are never wholly uncovered, thus preventing the oil 105 from spilling out into the casing.

The length of the stroke of the piston 110 may be varied by shifting the nuts 21 and 22 on the plunger or valve stem, the sleeves of which 23 may be arranged by pins 35 and 36 passing through slots 37 and 38 in the nuts. The nuts are provided with the 115 threaded extensions or sleeves 23 and 24 for the purpose of engaging the stem, the sleeves fitting slidably in the aperture in the projecting lug on the piston member (see Figs. 10 and 11). By removing these 120 pins the nuts may be shifted and then locked by rearranging the same. The air under shoulder of plunger 20 being exhausted at the same time that ports 10 and 11 are closed allows the plunger 20 of its own 125 weight and momentum to continue its descent until nut 21 has come in contact with lug 25. This action completes the opening of inlet 10 and gives an overlap to port 11.

Other modes of applying the principle of 130

our invention may be employed instead of the one explained, change being made as regards the mechanism herein disclosed, provided the means stated by any of the following claims or the equivalent of such stated means be employed.

We therefore particularly point out and distinctly claim as our invention:—

1. The combination with a tubular support open at its top, a piston member reciprocably mounted in said support, and means adapted to sharply arrest the fall of the said piston, thereby jarring the same, said support having inlet and exhaust openings below said piston; of a casing connecting such inlet opening with a fluid-pressure supply, said casing having two alined tubular chambers of unequal diameters; a plunger reciprocably mounted in such chambers in said casing and having a stem extending exteriorly of the same, said plunger being adapted to control such openings; spaced lugs attached to said stem; an extension on said piston slidably engaging such stem between said lugs; and a tube connecting such fluid-pressure supply with such chamber of larger diameter, the flow in such tube being controlled by the movement of said plunger.
2. The combination with a tubular support open at its top, a piston member reciprocably mounted in said support, and means adapted to sharply arrest the fall of the said piston, thereby jarring the same, said support having inlet and exhaust openings below said piston; of a casing connecting such inlet opening with a fluid-pressure supply, said casing having two alined chambers of unequal diameters; a plunger reciprocably mounted in such chambers in said casing and having a stem extending exteriorly of the same, said plunger being adapted to control such openings; means operatively connecting said piston and such stem; a cap, attached to such stem and movable therewith, extending over and fitting loosely around said casing; and means adapted to allow, the fluid-pressure used in reciprocating said plunger, to escape between said casing and said cap.

3. The combination with a tubular support open at its top, a piston member reciprocably mounted in said support, and means adapted to sharply arrest the fall of the said piston, thereby jarring the same, said support having inlet and exhaust openings below said piston; of a casing connecting such inlet opening with a fluid-pressure supply, said casing having two alined chambers of unequal diameters; a plunger reciprocably mounted in such chambers in said casing and having a stem extending exteriorly of the same, said plunger being adapted to control such openings; means operatively connecting said piston and such stem; a cap, attached to such stem and movable therewith, extending over and fitting loosely around said casing; a tube connecting such fluid-pressure supply and such chamber of larger diameter; and a second tube connecting the upper and lower parts of such larger chamber, the flow in such tubes and the exhaust between said cap and said casing being controlled by the movement of said plunger.

Signed by us this 31st day of August, 1912.

HARRY R. ATWATER.
EDWIN S. CARMAN.
